UNITED STATES PATENT OFFICE

1,989,560

HYDRAULICALLY CONTROLLED WHEEL SCRAPER

McLennen C. Slate, Albany, Oreg., assignor to
Slate Construction Company, Albany, Oreg.

Application February 1, 1930, Serial No. 425,247

10 Claims. (Cl. 37—140)

An important object of my invention is the provision of a scraper having efficient carrying capacity, which can be moved backward as well as forward, which can be raised to pass obstructions without losing the load, and over which the operator will have positive control at all times.

A further object of my invention is to provide a scraper of this character, the digging angle of which may be controlled at will by the operator.

10 Other objects and advantages of my invention will be apparent during the course of the following description.

In the accompanying drawings which form a part of this specification and wherein like characters of reference denote like parts throughout the same,

Figure 1 is a side elevation of my improved scraper in carrying position,

Figure 2 is a rear elevation thereof,

20 Figure 3 is a side elevation of the invention in digging position,

Figure 4 is a side elevation of my improved scraper showing the scraper body elevated to its highest position, and,

25 Figure 5 is a perspective view of my invention showing a modified wheel mounting and rear end construction.

In the drawings the numeral 28 designates a scraper body having spaced brackets 3, 4, 5 and 6 attached to the rear thereof by suitable fastening

30 means such as bolts 8. An axle 2 is mounted in the brackets and carries a pair of wheels 1 and 1' of sufficient size to support the scraper body 28 in a normally spaced relation with the ground.

35 A pair of spaced posts 31 are secured to the rear of the scraper body and extend a substantial distance thereabove. Dumping runners 29 are vertically arranged at the front of the scraper body and serve to support the cutting blade in spaced relation to the ground in dumping position.

40 A tongue 30 has an extension loop 32 to provide a slot 14 through which extends a pin 13 mounted in the posts 31. A tongue extension or bracket 27 is arranged on the upper side of the tongue and

45 is pivotally connected at 26 to a hydraulic cylinder 9. A piston 12 is arranged in the cylinder 9 and is operatively connected by a piston rod 20 with a pin 19 mounted in the upper ends of the posts 31. Conduit 10 communicates with the forward end of the hydraulic cylinder 9 and conduit 11 communicates with the rear end of the cylinder,

50 whereby fluid under pressure may be supplied to the hydraulic cylinder on either side of the piston 12.

55 A suitable cutting blade 15 extends transversely

across the front bottom portion of the scraper body 28. Suitable draft connecting rods 21 are pivotally connected at 22 to the bottom of the scraper body at opposite sides thereof, and have their forward ends connected at 23 to a lug 18 which is slidably arranged on the underside of the tongue 30 in the manner shown in my co-pending application 379,751, filed July 20, 1929 now Patent No. 1,791,485 of February 3, 1931. A suitable clevis 17 is pivotally mounted on the 10 forward end of the tongue and is shown connected to a tractor hitch device T. A lever 24 is pivotally secured to the tongue for releasing the lug 18 from its normal locked forward position, in the manner shown in my co-pending application referred to above.

When the slide lug 18 is released the weight of the scraper will cause it to tilt up on the runners or shoes 29 in a substantially upright dumping position.

In operation, when fluid under pressure is admitted through conduit 11 into the hydraulic cylinder 9 and the fluid already in the cylinder is allowed to escape through the outlet, the piston 12 will move forward in the cylinder and the pin 25 13 will move forward in the slot 14 and tilt the scraper body to cause cutting blade 15 to engage the ground at 16. This action will take place because clevis 17 in the forward end of the tongue, being attached to the tractor or other draft means, 30 is held in a fixed position above the surface of the ground. When the scraper is moved forward while in this position the earth will be scraped and loaded into the scraper body.

It will be seen that when the piston 12 is moved 35 towards the rear of the cylinder, the scraper is free to travel backwards on wheels 1 and 1' without dragging on the ground.

If it is desired to govern the depth of the cut, fluid may be forced under pressure into the cylinder to move the piston and consequently change the digging angle of the scraper by changing the position of the pin 13 in the slot 14. When the scraper is sufficiently loaded with earth, the piston is forced towards the rear of the cylinder to 40 raise the front end from the ground to the carrying position shown in Fig. 1, in which position the wheels support its entire weight.

The wheels 1 and 1' and the bracket assembly are heavy and strongly made and support a large 50 portion of the weight of the scraper as it moves along the ground. The scraper is lowered to a digging position while in motion and except under unusual conditions the wheels are always in engagement with the ground.

The scraper may be lifted over obstructions such as indicated at O by forcing the piston rearwardly in the cylinder and raising the blade 15 from the ground, as in Figure 4. When the obstruction is passed the scraper is lowered to its digging position.

Any suitable valve mechanism may be employed for controlling the flow of fluid under pressure to conduits 10 and 11 to and from the hydraulic cylinder 9.

It is within the spirit of my invention to utilize hydraulic control mechanism of the same type as that illustrated in detail in my co-pending application, Serial No. 398,685 filed October 10, 1929, the mechanism otherwise being as illustrated in the present invention.

Referring to Figure 5 of the drawings, there is illustrated a modified rear end construction in which a single central bracket 33 is utilized to perform the function of both the brackets 4 and 5, and upward extensions 34 of the central bracket take the place of the posts 31. The operation of the modified form of the invention shown in Figure 5 is the same as in the form of the invention shown in Figures 1 to 4, the modified construction, however, permitting the use of wider wheels than is possible with the use of the brackets 4 and 5.

The term "posts" is used to designate the bracket extensions 34 as well as the posts 31.

Having thus described my invention, what I claim and desire to protect by Letters Patent is:

1. In an apparatus of the character described, the combination with a scraper body, of a draft device connected with the scraper body adjacent the rear thereof, means connecting the draft device with the forward portion of the scraper body, and hydraulic apparatus operatively connecting the draft device with the scraper body and arranged to cause relative movement between the draft device and the scraper body during the digging, hauling and dumping operations of the scraper body.

2. In an apparatus of the character described, the combination with a scraper body, of a draft device operatively connected to said scraper body, said connection permitting limited sliding movement of the scraper body relative to the draft device, and a hydraulic apparatus associated with said sliding connection to cause relative movement between the draft device and scraper body.

3. In an apparatus of the character described, the combination with a scraper body, of brackets rigidly secured at the rear thereof, a wheel of substantial size journaled in said brackets and adapted to engage the ground, a post arranged adjacent the rear of the scraper body, draft means having a sliding connection with the post, and means to adjust said sliding connection to move the scraper body in an arc having the wheel journals as a center.

4. In an apparatus of the character described, the combination with a wheeled scraper, of a draft device having a sliding connection with the rear portion thereof, a hydraulic cylinder connected to one of said members, a piston arranged in said cylinder and connected to the other of said members, and means to convey fluid under pressure into said cylinder to move the piston and cause relative movement between the scraper and draft device.

5. In an apparatus of the character described, the combination with a scraper body, of brackets rigidly secured to the rear portion thereof, a

wheel of substantial size journaled in said brackets and extending below the rear portion of the scraper, a post extending above the scraper adjacent the rear thereof, a draft device having a sliding connection with said post at a point spaced from its upper end, and a hydraulic apparatus connecting said draft device with the post at a point spaced above the sliding connection and adapted to cause relative movement between the draft device and scraper body.

6. In an apparatus of the character described, the combination with a scraper body, of a post connected to said scraper body adjacent the rear thereof and extending a substantial distance thereabove, a draft device having a sliding connection with said post, a bracket on said draft device, a hydraulic cylinder secured to said bracket, a piston arranged in said cylinder and pivotally connected to the post, and means for supplying fluid under pressure to said hydraulic cylinder.

7. In an apparatus of the character described, the combination with a scraper body, of a post extending thereabove adjacent the rear thereof, a draft device slidably connected with said post at a point spaced from its top, a hydraulic apparatus connecting the draft device with the post at a point spaced above the slidable connection for causing relative movement between the draft device and the scraper body, and a releasable connection between the front of the scraper body and the draft device.

8. In an apparatus of the character described, the combination with a scraper body, of brackets rigidly secured to the rear thereof, relatively wide wheels journaled in said brackets, and extending below the bottom of the scraper, a post extending above the scraper body adjacent the rear thereof, a draft device having a sliding connection with the post, a hydraulic piston and cylinder connecting the post with the draft device, means to force fluid under pressure into the hydraulic cylinder to cause relative movement between the scraper body and draft device, and a releasable connection between the front portion of the scraper body and the draft device.

9. The combination of a scraper body having a cutting blade, brackets affixed to the rear of the scraper body, wheels carried by the brackets and of sufficient size to normally hold the bottom of the scraper body spaced from the ground, upstanding members affixed to the rear of the scraper body, a hydraulic cylinder, a piston slidably mounted in the hydraulic cylinder, said piston having a piston rod operatively connected with the upper ends of the upstanding members affixed to the scraper, a tongue for the scraper, said tongue being adapted to be attached to a draft means, a pin mounted in the upstanding elements and spaced from the upper end thereof, the aforesaid tongue having a rear extension portion provided with a slot to slidably receive the aforesaid pin, whereby on operation of the piston the scraper body may be tilted to a desired digging angle and returned to its original position by hydraulic pressure control.

10. The combination of a scraper body having a cutting blade, outer brackets substantially aligned with the side of the scraper body at the rear thereof, a single central bracket, relatively wide wheels carried by the aforesaid brackets and normally holding the bottom of the scraper body spaced from the ground, upstanding members fixedly mounted on the rear of the scraper

body, hydraulic cylinder and piston mechanism operatively connected with the upper end of the upstanding elements, a tongue for the scraper, said tongue being adapted to be attached to a draft means, a pin mounted in the upstanding elements and spaced from the upper end thereof, the aforesaid tongue having a rear extension

portion including a slot to slidably receive the aforesaid pin, whereby on operation of the hydraulic control mechanism the scraper body may be tilted to a desired digging angle or returned to its original position at will.
